UNITED STATES PATENT OFFICE.

GODFRIED LAUBE, OF SANTA MONICA, CALIFORNIA, ASSIGNOR OF ONE-HALF TO JOHN C. MILLER, OF LOS ANGELES, CALIFORNIA.

DOOR-HOLDER.

Specification of Letters Patent.

Patented May 7, 1907.

No. 852,513.

Application filed August 13, 1906. Serial No. 330,356.

To all whom it may concern:

Be it known that I, GODFRIED LAUBE, a citizen of the United States of America, residing at Santa Monica, in the county of Los Angeles and State of California, have invented certain new and useful Improvements in Door-Holders, of which the following is a specification, reference being had therein to the accompanying drawing.

10 This invention relates to certain new and useful improvements in door holders, and the invention has for its object to provide a simple, inexpensive and portable door holder, which will be noiseless and take a positive grip upon a carpet, matting, linoleum, or a bare floor.

Another object of this invention is to provide a door holder which will not tear or injure the carpet or floor, nor scar or mar a door.

20 A further object of my invention is to provide an ornamental, easily operated holder for doors, applicable to various kinds and sizes of doors.

25 A still further object of this invention is to provide a combination door holder and hat holder capable of being used together or as either holder.

With the above and other objects in view, 30 which will more readily appear as the invention is better understood, the same consists in the novel construction, combination and arrangement of parts to be presently described, illustrated and specifically pointed out in the claims.

35 Referring to the drawing forming part of this specification, like numerals of reference designate corresponding parts throughout the several views, in which:

40 Figure 1 is a perspective view of my improved door holder as holding a door in an open position, Fig. 2 is a longitudinal sectional view of my improved door holder, Fig. 3 is a perspective view of the upper end 45 of a handle or hat holder forming part of my improved door holder, Fig. 4 is a cross sectional view of the door holder, and Fig. 5 is a fragmentary section of the holder as supporting a hat.

50 To put my invention into practice, I construct my holder of a plate 1 having an inclined or beveled surface 2. The plate is adapted to slip under the outer edge of the door 3 and wedge said door, whereby it can-

not be moved until the plate is removed. To 55 insure a positive gripping of the door 3 by the plate 1, I provide the beveled surface 2 of the plate with two longitudinally disposed ribs 4 preferably formed by two pieces of wire having their ends fixed in the plate 1, as at 5. 60 The door is adapted to impinge these wires and prevent the beveled surface 2 of the plate 1 from being worn.

The sides of the plate 1 are provided with ornamental plates 6, these plates being preferably cut to represent the outline of a resting animal such as a dog. The forward end 7 of the plate 1 can be ornamented or decorated to further assist in the representation of an animal, this end of the plate being preferably carved to represent the fore legs and feet of a dog. The extreme end of the plate is provided with a covering 8 of a suitable durable material adapted to protect the door holder and a shoe, when the holder is being 75 forced under the door by a person's foot.

The plates 6 have their rear edges covered with a durable, flexible material 9, as rubber, to protect the sides of the door and the holder, when said holder is placed in engagement with the door.

Detachably secured in the forward end 7 of the plate 1 is a vertically disposed rod 10 having its upper end bent to form a loop 11, this rod and loop serving functionally as a 85 handle for manipulating the holder, and as a support or rack for a hat.

By the novel construction of my improved holder, it will be observed that since the holder is not a fixture upon a door, it can be 90 readily moved about and used in connection with any door. When engaging a door the holder can be observed upon both sides of the door, thus indicating that the door is fastened.

My improved holder is made of a sufficient 95 width to accommodate doors of various thickness, and the wedge-shaped plate 1 is made thick enough to fill the space between any door and a floor, irrespective of the height of the threshold.

It will be apparent from the foregoing description taken in connection with the drawing, that I have devised a simple door holder having numerous advantages over the ordinary holders attached to doors.

What I claim and desire to secure by Letters Patent, is:—

1. A door holder embodying a plate hav-

- ing a beveled surface, longitudinally disposed ribs mounted upon said surface, a cover secured to the forward end of said plate, ornamental side plates carried by said beveled plate, covers secured to the rear edges of said side plates, a vertically disposed rod detachably mounted in the forward end of said beveled plate and having a loop upon its upper end, substantially as described.
- 10 2. A door holder embodying a beveled plate, ribs carried by the beveled surface of said plate, ornamental side plates carried by said beveled plate, a vertically disposed rod mounted in said plate and having a loop upon its upper end, and coverings for portions of said plates, substantially as described.
- 15 3. A door holder consisting of a beveled plate adapted to engage under a door, ornamental side plates carried by said beveled plate, and a handle, substantially as described.
4. A combined hat and door holder consisting of a beveled plate, adapted to engage under a door, and a rod carried by said plate and adapted to support a hat, substantially as described.

In testimony whereof I affix my signature in the presence of two witnesses:

GODFRIED LAUBE.
